CALCULATING MACHINE

Carl M. Friden, Pleasanton, Calif., assignor to
Friden Calculating Machine Co., Inc., a corpora-
tion of California

Application July 29, 1940, Serial No. 348,099

10 Claims.

(Cl. 74—527)

This invention relates to calculating machines and is concerned more particularly with the provision of improvements designed to minimize the noise and to obtain silent operation of reciprocating or oscillatory parts.

In calculating machines and similar equipment of the power-driven type, there are numerous parts which are driven cyclically to oscillate, reciprocate, or pivot about axes, and because of the high speed operation of modern machines running between four hundred to one thousand R. P. M., the noise considerations involved with the operation of such parts present a source of considerable annoyance and trouble to operators, particularly in offices where a large number of machines are employed at the same time. It is highly desirable, therefore, that the operation of calculating machines and similar equipment be as silent as possible, particularly when used in large groups or in offices where conversations and other business must be transacted while the machine is operated.

It is a general object of the invention to provide means for silencing the operation of the moving parts in equipment such as calculating machines.

Another object of the invention is to provide an improved shift mechanism of a smooth and even action of silent character.

Another object of the invention is to provide a silencing means for the operation of reciprocating or oscillating parts of a calculating machine.

Other objects and advantages of the invention will be apparent from the following description of certain preferred embodiments thereof, as illustrated in the accompanying drawings, in which:

Figure 1 is a side elevational view partly in section of a calculating machine embodying the invention;

Figure 2 is a fragmentary sectional elevation illustrating certain of the shift control connections;

Figure 3 is an enlarged rear elevational view of the shifting mechanism in cooperative relation with respect to the carriage;

Figure 4 is a view similar to Figure 3 but showing the shift mechanism during operation. As shown, the parts are in half cycle position during a shifting operation;

Figure 5 is a rear elevational view similar to Figures 3 and 4 but showing the parts as positioned in a full cycle position but operating during a shifting operation;

Figure 6 is a vertical cross sectional view taken along the line 6—6 of Figure 3.

Figure 7 is a horizontal cross sectional view taken along the line 7—7 in Figure 3.

The calculating machine selected for illustration in connection with the invention is of the general type described in my Patent No. 2,229,889, dated January 28, 1941, as modified in the co-pending application of Carl M. Friden and Anthony B. Machado, Serial No. 343,368, filed July 1, 1940. The machine includes a base 10 upon which side plates 11 and 12 of the frame construction are mounted within the casing 13. The frame of the machine also includes transverse brackets 16, 17, 18 and 19 which extend between the side plates 11 and 12 and are secured thereto in any convenient manner.

The machine includes a shiftable register carriage 21 which is mounted for endwise sliding movement on frame brackets 16 and 19 by means of rollers 22. The register carriage 21 serves to mount the numeral wheels 23 of the revolutions counter having an actuator 24 of suitable construction associated therewith. The carriage 21 also mounts numeral wheels 26 of the accumulator which are suitably journaled in carriage frame 27 and adapted for actuation through suitable plus-minus gearing 28 having a sliding driving engagement with a shaft 29. Each shaft 29 receives differential increments of movement in a known manner from the associated actuating cylinder 31 under control of the usual bank of numeral keys 32 associated therewith. The sign character of the registration is controlled by shifting of the plus-minus gearing 28 under the control of a strap 33 which is mounted by suitable upright arms 34 on a transverse rockable shaft 36 which may be controlled in any convenient manner in performing calculating operations.

The drive for the actuating cylinders 31 and for all other motor-driven or power operations of the machine is derived from motor 41 having its drive shaft 42 connected by gearing 43 with the driving element or ratchet 44 of a cyclically operable clutch. Ratchet 44 is journaled on driven shaft 46 which is suitably connected to drive actuating shafts 47 on which the cylinders 31 are mounted. The cyclic operation of the clutch is controlled by means of clutch dog 48 carried by driven part 49 of the clutch and spring-urged by means of spring 51 to clutch-engaging position.

The engagement of the clutch is controlled by means of clutch control lever 52 pivoted at 53 on side plate 12. Control lever 52 is connected by link 54 with the pivoted lever 56 which is pivotally connected at its lower end with a second piv-

oted lever 57 which controls the opening and closing of motor circuit contacts 58.

Shift mechanism.—Means are provided for shifting the carriage selectively in either direction for one or more ordinal steps of movement, and the shifting means is preferably operated from the actuating shafts 47 and the cylically operable clutch under the control of a pair of manually depressible, freely retractable shift keys which control shifting of the carriage for one or more steps of movement in accordance with the length of time (the number of machine cycles) for which they are maintained depressed.

Referring to Figure 1, the shift control keys are indicated at 70 and 71 and are mounted for vertical sliding movement on side plate 12 by suitable pin and slot connections. Suitable spring means (not shown) may be provided for maintaining keys 70 and 71 in their raised positions as shown in Figure 1. As seen in Figure 1, each key 70 and 71 is provided with a pin 72 which projects to either side of the key. One end of each pin 72 cooperates with a suitable cam surface on a claw arm 73 secured to lever 56 for rocking movement therewith. Therefore, upon depression of either shift key 70 and 71, levers 56 and 57 are rocked to engage the clutch and close the motor circuit contacts 58.

Prior to the engagement of the clutch and closing of the motor contacts, each of keys 70 and 71 is operative to engage corresponding shift connections, so that selective shifting movement of the carriage 21 in either direction for one or more ordinal positions is determined by depression and release of the respective keys. As seen in Figure 2, the respective left-hand ends of pin 72 carried by the keys 70 and 71 are operatively related to arms 76 and 77, respectively, which are carried by sleeve 78 and shaft 79 on which sleeve 78 is pivotally mounted.

As seen in Figure 2, sleeve 78 also carries a depending arm 81 which is operatively engaged to operate a push rod 87 which may be slidably mounted for endwise movement in cross brackets 17, 18 and 88 (Figures 1 and 2). Shaft 79 also carries a depending arm 81 (not shown) which is similarly related to a push rod 89 (Figure 7).

The respective push rods 87 and 89 upon depression of the respective keys 71 and 70 serve to enable respective drive connections from the actuating shafts to a shift drive gear in a manner to be described. As seen in Figures 6 and 7, the push rods 87 and 89 are telescopically engaged within respective collars 91, the respective collars 91 being secured to respective forked arms 92 and 93. Respective springs 94 compressed between collars 91 and washers 96 on respective rods 87 and 89 serve to maintain each telescopic push rod connection in extended position.

Forked arms 92 and 93 (Figures 1, 6 and 7) engage respective annular grooves in shiftable drive-establishing collars 97 and 98, which have endwise-slidable driving engagement with fixed collars 99 secured on the rearward ends of adjacent actuating shafts 47.

Collars 97 and 98 (Figure 7) are provided with respective driving teeth 101 for engagement with opposed driving notches 102 in respective gear sleeves 103 and 104. Gear sleeves 103 and 104 are journaled in brackets 16 and plate 106 mounted on brackets 16 by means of suitable spacers and bolt connections 107.

As seen in Figures 1, 6, and 7, gear sleeve 103 carries gear 111 which meshes with wide idler gear 112 suitably journaled on bracket 16 and 75

plate 106. Idler gear 112 also meshes with large gear 113 (Figures 6 and 7) of a double gear assembly including a small gear 114 meshing with shift drive gear 116. The gear assembly 113 and 114 are carried by shaft 117 suitably journaled in brackets 16 and plate 106. Gear 116 is carried by shaft 118 suitably journaled in brackets 16 and in portion 106a (Figure 6) of plate 106.

As seen in Figure 6, gear sleeve 104 carries gear 121 which meshes directly with gear 113 of the double gear assembly. The result is that gear sleeves 103 and 104, when driven, serve to drive the gear train including gears 113, 114, and 116 in opposite direction. The gearing provides a drive ratio of four to one, so that each rotation of the gear sleeve 103 or gear sleeve 104 will provide a one-quarter rotation of gear 116.

As seen most clearly in Figures 1 and 3, shaft 118 which carries shift drive gear 116 also carries a drive plate 131 carrying four equally spaced shift drive pins 132 for engagement with notches 133 of shift rack 134 on carriage 21. As seen in Figure 3, yieldable pawl 136 pivoted at 137 on rack 134 provides one wall of one end slot 133, so that the disc 131 upon clockwise rotation, as shown in Figure 3, will be ineffective to shift the carriage past its end position but can become effective upon counter-clockwise movement to shift the carriage from its left-most position as viewed from the front of the machine. A similar yieldable pawl may be provided at the other end of rack 134.

The arrangement is such that depression of key 70 operates through the associated linkage to engage drive tooth 101 with its corresponding notch 102 (Figure 7) of gear sleeve 103 to effect right-hand shifting of the carriage (i. e., to the left as shown in Figure 3) by causing counter-clockwise rotation of disc 131. Correspondingly, depression of shift key 71 causes shifting of the carriage to the left as viewed from the front of the machine by engagement of drive collar 98 with gear sleeve 104 to effect counter-clockwise rotation of disc 131 as viewed in Figure 3.

Means are provided for locking the carriage in any shifted position thereof, said means being releasable upon operation of either shift key. As best seen in Figures 3 and 4, the shift disc 131 carries four pins 166 equally spaced thereabout for cooperation with the upper ends of a pair of scissor levers 167 and 168 pivoted at 169 and 170 respectively on plate 106 and having a pin and slot connection 171. Stop arms 167 and 168 are urged together into operative relation with respect to pins 166 by spring 172 tensioned between the lower ends thereof. Stop arm 167 carries a depending arm 173 which lies in front of an ear 174 (Figures 3 and 7) of a link 176 pivotally connected to similar bell cranks 177 which are pivoted on horizontal axes on respective brackets 178. Each bell crank 177 has an arm 179 lying in front of a depending tab 180 of respective push forks 92 and 93 and together with the link 176 form a parallel linkage which, upon operation of either of push rods 87 and 89, is operated to rock the stop arms 167 and 168 to disengaged position, as shown in Figure 4, for example.

The shift drive disc 131 has centralizing means associated therewith which operates to insure accurate positioning of the carriage in any shifted position thereof and thereby obtain proper alignment of the ordinal numeral wheels with their actuating drive connections. The centralizing

means is equipped with silencing means by the provision of a two-part centralizer construction having shock-absorbing and sound-deadening means interposed therebetween. The follower part engages the centralizing disc at all times under a light spring pressure, while the actual centralizing force is applied through the sound-deadening means under heavy spring pressure applied to the second or actuating part of the centralizing means. The centralizer actuating part is disabled during plural cycle operations of the shifting mechanism until the carriage is in the desired shifted position, so that during plural cycle operation the follower part which constantly oscillates is under only light spring pressure and hence makes a minimum of noise, while presenting a hard metallic wearing surface. The actuating part when released at the end of the operation exerts its heavy centralizing force through the sound deadening means.

As seen in Figure 3, the shift drive disc 131 is provided with four equally spaced centralizing depressions 181 which are in equally spaced apart relation between the pins 132.

Opposite depressions 181 of the disc 131 are engaged by respective rollers 182 which are carried at the upper end of respective follower arms 183, 184 which are pivoted at 186 and 187 respectively on plate 106. The arms 183 and 184 are connected by a comparatively light tension spring 188 which serves to urge rollers 182 into engagement with the disc 131 at all times. By virtue of their light spring 188 the arms 183 and 184 can follow the periphery of disc 131 with a minimum of noise.

Associated with the centralizing arms 183 and 184 (Figure 3) are a pair of more strongly spring-urged operating centralizers which are latched out of active position during plural cycle shifting operations. For this purpose a pair of operating centralizing bell cranks 191 and 192 are also pivoted on pins 107 and are connected by strong tension spring 193. The upper arm of bell cranks 191 and 192 is provided with a laterally extending ear 194 which is parallel to a similar ear 196 of the associated arm 183. A sound deadening button 197 of rubber or other similar silencing material is secured to ear 194 for engagement with ear 196. For example, ear 194 may be apertured and button 197 may be provided with an integral extension 198 which has a press fit in the apertured ear.

The lower arms of respective bell cranks 191 and 192 (Figure 3) extend into overlapping relation and are connected so that the bell cranks move together. As seen in Figure 3, the bell crank 191 is provided with reduced portion 199 on its lower arm which overlies the pin 201 carried by bell crank 192. Bell crank 192 on its lower arm carries a downwardly extending ear 202 which, in the centralizing position of bell cranks 191 and 192, is positioned alongside the upper end 203 of a latch lever 204 which is pivoted at 206 on plate 106. Lever 204 is urged in a clockwise direction, as viewed in Figure 3, by spring 207 secured thereto and to arm 168.

From the foregoing description it will be seen that upon rotation of the disc 131 the rollers 182 are lifted from the depressions 181 to raised portions 208 thereof, as shown in Figure 4, for example, and at the same time carry bell cranks 191 and 192 therewith. When the lower arms of the bell cranks have been lifted as shown in Figure 5, the latch end 203 of the latch lever 204 will snap under the ear 202, to maintain the bell

cranks 191 and 192 out of engagement with the centralizing arms 183 and 184.

Automatically operable means are provided for maintaining the latch 204 active during plural cycle operation of the shifting mechanism and for disabling the latch upon completion of the desired shifting operation. For this purpose, the lever 204 is provided with an arm 211 which overlies a roller 213 carried by a cam follower arm 214 pivoted at 216 on plate 153 and urged in a clockwise direction by spring 217. Cam follower arm 214 is provided with a tooth 218 which is adapted in the full-cycle position of the parts to seat in a notch 219 of a cam disc 221 secured on the extended end 222 of one of actuating shafts 47. Disc 221 is adapted to rotate in a clockwise direction, as viewed in Figure 3, and the trailing side of its notch 219 is provided with a cam face cooperating with the cam face of tooth 218 to move the arm 214 and allow latch lever 204 to move into latching engagement with tooth 202.

Thus latch lever 204 moves into latching engagement with the bell cranks 191 and 192 when they are moved to inactive position by the engagement of rollers 182 with the high portions 208 of disc 131. It will be noted that the contour of cam disc 221 is slightly spiraled to provide a higher radial depth at point *a* on one side of the cam notch 219 with respect to point *b* at the other side thereof, the action being such that upon continuous rotation of cam disc 221 during a plural cycle operation, the cam follower arm 214 does not have sufficient time to seat in the notch 219. Thus while a plural cycle shifting operation is in progress, the centralizing bell cranks 191 and 192 are maintained in the displaced position shown in Figures 4 and 5, so that their action on the disc 131 is avoided. This results in a smooth, even shifting operation and in a substantial reduction of noise of operation which would occur if the centralizing rollers 182 which follow the periphery of the disc 131 were under heavy spring pressure at all times. Also, when the operating bell cranks 191 and 192 are released their impact on arms 183 and 184 is deadened and silenced by the rubber silencers 197 so that the noise resulting therefrom is minimized.

Means may be provided to prevent operation of the centralizer latching means during division operation to enable functioning of the centralizing operating bell cranks irrespective of the continuous cycle operation of the actuating means in performing division. Referring to Figures 1, 4, 5, shaft 224 of a conventional form of division mechanism is settable in a clockwise direction through arm 225 and pin 226 of the division setting mechanism. Shaft 224 carries an arm 227 having its end normally above and out of the path of an extension 228 of latch lever 204. Upon setting of shaft 224 during division arm 227 moves into blocking relation with respect to extension 228 of latching lever 204 to block operative movement thereof during division.

In operation, with the carriage positioned as shown in Figure 3, for example, as the shift key is depressed and the drive for the cam disc 131 is enabled during the first half of the first shift cycle the cam disc moves from the position shown in Figure 3 to that shown in Figure 4, so that arm 183, for example, and bell crank 191 are moved back or oscillated a sufficient amount so that the latch lever 204 can move into latching engagement with the bell cranks 191 and 192. At the

same time the follower arm 214 is displaced by the cam disc 221 to permit such latching movement. Subsequently, as long as the follower arm is held out by continued rotation of the cam disc 221, for example, as shown in Figure 5, the bell cranks 191 and 192 are latched in disengaged position as shown in Figure 5. At the end of the operation, when the cam disc 221 reaches its full cycle position, the cam follower arm 214 moves into its seated position as shown in Figure 3 to move the latch lever 204 to inactive position. Thus the centralizing bell cranks 191 and 192 can move into engagement with the centralizing arms 183 and 184, and this movement is effected without substantial noise because of the interposed rubber silencing buttons 197.

I claim:

1. In a calculating machine, drive means including a disc rotatable in cyclic fashion, a centralizing element constantly engaging said disc under light spring pressure, a second element for urging said first element towards said part under heavy spring pressure, sound-deadening means for transmitting force from said second element to said first element, and means for latching said second element in inactive position, said latching means including means for effecting delatching of said element upon termination of the cyclic operation of said disc.

2. In a calculating machine, drive means including a part movable in cyclic fashion, an element constantly engaging said part under light spring pressure, a second element for urging said first element toward said part under heavy spring pressure, and means for latching said second element in inactive position.

3. In a calculating machine, drive means including a part movable in cyclic fashion, an element constantly engaging said part under light spring pressure, a second element for urging said first element toward said part under heavy spring pressure, sound deadening means for transmitting force from said second element to said first element, and means for latching said second element in inactive position.

4. In a calculating machine having a cyclically operable mechanism, means for centralizing said mechanism including a centralizing disc mounted for rotation with said mechanism and a two-part follower construction including one part constantly engaged with said disc under spring pressure and another part for urging said first part against said disc with additional spring pressure, and means for latching said other part in inactive position during a plural cycle operation of said mechanism.

5. In a calculating machine having a cyclically operable mechanism, means for centralizing said mechanism including a centralizing disc mounted for rotation with said mechanism and a two-part follower construction including one part constantly engaged with said disc under spring pressure and another part for urging said first part against said disc with additional spring

pressure, said centralizing means also including thrust-transmitting silencing means interposed between said parts, and means for latching said other part in inactive position during a plural cycle operation of said mechanism.

6. In a calculating machine having a cyclically operable mechanism, means for centralizing said mechanism including a centralizing cam disc, a follower arm for constantly engaging said disc under spring pressure, and an actuating arm for engaging said first-named arm under spring pressure to supply additional force for the centralizing operation.

7. In a calculating machine having a cyclically operable mechanism, means for centralizing said mechanism including a centralizing cam disc, a follower arm for constantly engaging said disc under spring pressure, an actuating arm for engaging said first-named arm under additional spring pressure, and a silencer pad for transmitting force from said actuating arm to said follower arm.

8. In a calculating machine having a cyclically operable mechanism, means for centralizing said mechanism, said centralizing means including a cam disc having a centralizing depression and a spring-urged arm for engagement with said depression, said centralizing means also including a second spring-urged arm for urging said first-named arm against said disc, and means for latching said second arm in inactive position during a plural cycle operation of said mechanism.

9. In a calculating machine having a cyclically operable mechanism, means for centralizing said mechanism, said centralizing means including a cam disc and a two-part follower construction having thrust-transmitting sound deadening means interposed between the two parts of said follower construction, one of said parts constantly engaging said disc, means for latching the other part of said two-part follower in inactive position during a plural cycle operation of said mechanism, and means for causing delatching of said other part upon termination of the drive for said mechanism.

10. In a calculating machine having a cyclically operable mechanism, means for centralizing said mechanism, said centralizing means including in a cam disc and a two-part follower construction having thrust-transmitting sound deadening means interposed between the two parts of said follower construction, one of said parts constantly engaging said disc under spring pressure, and the other of said parts urging said one part towards said disc under additional spring pressure, means for latching the other part of said centralizing means in inactive position during a plural cycle operation of said mechanism, and means for causing delatching of said other part upon termination of the drive for said mechanism.

CARL M. FRIDEN.
